STEERING ACCESSORY

John Lester Barr, Chevy Chase, Md., and James C. Houghton, Washington, D. C.; said Houghton assignor to said Barr

Application November 3, 1933, Serial No. 696,579
Renewed May 17, 1935

13 Claims. (Cl. 280—150)

Our invention relates to means for relieving the weight of one or more of the steering wheels of a vehicle so that the steering wheels may be turned more readily.

5 Heretofore where a universally suspended leg or compression element is dropped from say the front axle of a car, there are occasions when it tends to engage the ground while in a position laterally displaced from the vertical. Therefore, when the car is driven either backward or forward to relieve the weight on the steering wheels, the laterally displaced compression element may be in such position as to inefficiently perform its function.

15 An object of our invention is to laterally align a compression element of the type disclosed in the drawings, so that an equal amount of lift may be obtained in successive operations of the compression element, such as occur when the 20 foot of the compression element is in contact with the ground and the car is either backed on to, or driven forward on to, the compression element.

25 Yet another object of our invention is to tend to prevent undue shifting of the foot of the compression element or leg by reason of rotation or other phenomena which tend to prevent biting of the foot into the roadway. This trouble is sometimes encountered in constructions which 30 have universal connection of the foot with the compression element.

These are not the only objects of the invention, and as the description proceeds other objects will 35 become apparent. It is desired that the coverage of the claims be limited solely by the showing of the prior art and the terminology of the claims themselves.

In the drawings:

40 Fig. 1 is a perspective view showing our device in place on a car;

Fig. 2 is a detail view in front elevation of the centering ear construction;

45 Fig. 3 is a detail view in front elevation of the centering ear construction showing the compression element laterally displaced, and one of the tension ears exerting a restoring force;

Fig. 4 is a view in side elevation of the front axle of a car with our device in place;

50 Fig. 5 is a view taken along the line 5—5 of Figure 4;

Fig. 6 is a view taken along the line 6—6 of Figure 4;

Fig. 7 is a bottom plan view, partly in section, with our device in place on an automobile axle.

55 Referring to the drawings, we have shown in

perspective, and particularly in Figure 1, the front wheels 1 of an automobile connected to a front axle 2. There is shown a steering wheel 3 having a steering post 4. Mounted on the steering post 4 on a hook 5 is a ring 6, to which 5 is attached a wire 7, which may be of the Bowden type. The wire 7 runs through a sheath 8 attached at 9 to the steering post 4. The sheath 8 terminates in a hollow screw and nut fixture which we have designated generally by the numeral 10, which is bolted to a support 11 carried by support rods 12. The support 11 is bolted, by means of nuts 13, to the support rods 12.

The wire 7 is adapted to slide within the sheath 8. The lower end of the wire, opposite from the 15 end attached to the ring 6, is attached to a collar 14 which fits around a compression element 15. There is a nut and bolt construction 16 which fastens together the collar 14 and the wire 7.

The compression element 15 is provided with an upper ball 16', and a lower ball 17. The lower ball 17 is carried by a male member 18, provided with screw-threads 19, which is screw-threaded within the hollow end 18' of the compression element 15. A lock nut 21 holds the male member 18 in its adjusted position with respect to the hollow end 18' of the compression member 15. The upper ball 16' is adapted to rest in a socket element 22 provided with a side 25 aperture having a cylindrical portion 23 and a conical portion 24. The construction of the groove 23 and the conical portion 24 is such as to permit the stem 25 on which the ball 16' is mounted to enter in the groove 23, and the upper 30 tapered part of the compression member 15 to enter the conical portion 24 when the compression element is raised into its uppermost position.

It will be noted from an inspection of Figure 1 that there are two hooks shown on the steering post 4, namely the hook 5 above mentioned and another hook 5'. The upper hook 5' is so located that when the ring 6 is fitted over the upper hook 5', the compression element 15 will be in its raised position.

The socket 22 is provided with a holding plate 26 which may be attached by means of screws 22', or otherwise suitably fastened over the socket member 22 so as to hold the ball 16' in position.

U-bolt clamps 27 fit over the upper part of the axle and are bolted into enlarged ears 28 formed on the socket member 22. The U-bolts 27 are held in place by nuts 29.

The support rods 12 pass through the socket 55

element 22 and are provided with heads 31. Between the heads 31 and the socket elements 22 we have placed the ends 32 of U-shaped metallic tension ears 33. These ears are pivoted on the 5 rods 12, the other ends of the ears being pivoted on the other side of the socket element 22, the rods 12 passing through the ends of the ears and projecting outwardly, as plainly visible in Figures 4 and 7. The ends of the ears opposite the 10 heads 31 are provided with projecting portions 34 having bent over terminal sections 35.

Encircling the rods 12 are helical tensioning springs 36 whose other ends are adapted to contact the bent over portions 35 of the extensions 15 34 which are formed on the ears 33. These springs 36 encircle the rods 12 and are adapted at their opposite ends to contact with projecting elements 37 formed on the support 11.

The ears 33 are adapted normally to occupy 20 an approximately vertical position, see Figures 2 and 6, and are held downwardly in this position. Any movement from this position is against the tension of the springs 36, which resist such movement. The ears are adapted to 25 rest against stops 38. The stops are so positioned and the parts so constructed that normally there shall be a clearance between the compression member 15 and the ears 33. This is to permit free forward and backward movement of the 30 compression element. When, however, the compression element 15 varies sufficiently from the vertical in the direction of either of the compression ears, it encounters one of them and the tension springs 36 will exert a force tending to 35 prevent such movement of the compression element 15.

In Figure 3 we have shown the parts in such 40 position that there is exerted on the compression element or leg 15 a force by one of the compression ears 33 which tends to restore it to its normal position between the ears 33. The function of the ears is two-fold: first, in that they tend to return the leg to the middle position after each operation of raising the car on the leg 45 by driving over it, so that there shall be approximately an equal lift each time the operation is performed; and secondly, in the particular instances shown where there is provided a circular foot 39 in which the ball 17 is socketed and where 50 there is a tendency for the foot to rotate and slide sidewise, to prevent this sliding and thereby to increase the "bite" of the device on the roadway. The centering ears minimize this effect and tend to resist the displacement of the leg 55 from its middle position and to insure early and satisfactory "bite" of the foot on the roadway.

We claim:

1. A device of the character described comprising a vehicle, a compression element, a universal pivot for the element on the vehicle, and resilient tension means opposing movement in two directions only.

2. A device of the character described comprising a vehicle, a compression element, a universal pivot for the element on the vehicle, and spring pressed tension ears opposing free movement of the element in two directions only.

3. A device of the character described comprising a vehicle, a compression element, a universal pivot for the element on the vehicle, ears pivoted on opposite sides of the element, and springs tending to hold the ears in the vertical position.

4. A device of the character described comprising a vehicle, a compression element, a uni-

versal pivot for the element on the vehicle, ears pivoted on the opposite sides of the element, support rods, springs on the support rods, one end of each spring being fixed and the other end bearing against an ear, tending to hold it in the vertical position.

5. A device of the character described comprising a vehicle, a compression element, a universal pivot for the element on the vehicle, ears pivoted on the opposite sides of the element having movement approximating the vertical, stop means preventing movement beyond the vertical towards the element, and springs tending to hold the ears in a vertical position.

6. A device of the character described comprising a vehicle, a compression element, a universal pivot for the element on the vehicle, and spring pressed U-shaped metallic ears opposing the free movement of the element in two directions.

7. A device of the character described comprising a vehicle, a compression element, a universal pivot for the element on the car, U-shaped metallic tension ears pivoted on opposite sides of the element, and springs tending to hold the ears in the vertical position.

8. A device of the character described comprising a vehicle, a compression element, a universal pivot for the element on the vehicle, U-shaped metallic tension ears pivoted on opposite sides of the element, support rods, springs on the support rods, one end of each spring being fixed and the other end bearing against an ear tending to hold it in the vertical position.

9. A device of the character described comprising a vehicle, a compression element, a universal pivot for the element on the vehicle, a foot universally pivoted to the compression element, and spring means opposing tension to movement of the element in two directions.

10. A device of the character described comprising a vehicle, a compression element, a universal pivot for the element on the vehicle, a foot universally pivoted to the element, ears pivoted on the opposite sides of the element, and springs tensioned to hold the ears in the vertical position.

11. A device of the character described comprising a vehicle, a compression element, a universal pivot for the element on the vehicle, a foot universally pivoted to the element, ears pivoted on the opposite sides of the element, support rods, springs on the support rods, one end of each spring being fixed and the other end bearing against an ear, tending to hold it in the vertical position.

12. A device of the character described comprising a vehicle, a compression element, a pivot to attach said element to the vehicle, said pivot allowing motion of said compression element in mutually transverse directions, guiding means allowing said compression element to move freely in one of said directions, and resilient means acting on said guiding means to oppose movement of said compression element in the other of said directions.

13. A device of the character described comprising a vehicle, a compression element, a universal pivot for the element on the vehicle to permit it to twist as well as move laterally and back and forth, and guiding means for the compression element tending to prevent lateral displacement only.

JOHN LESTER BARR.
